HIGH PRESSURE GAUGE HOUSING

Jord O. Nelson, Paramount, Calif., assignor to Eltra
Corporation, Toledo, Ohio

Filed Jan. 14, 1966, Ser. No. 599

Term of patent 7 years

(Cl. D52—6)

Fig. 1

Fig. 4

Fig. 2

Fig. 5

Fig. 3

FIG. 1 is an isometric view of a high pressure gauge housing showing my new design, a similar view taken clockwise to the left at approximately sixty degrees being substantially a mirror image thereof;

FIG. 2 is a front elevational view of the housing;

FIG. 3 is a rear elevational view of the housing;

FIG. 4 is a top plan view thereof; and

FIG. 5 is a bottom plan view thereof.

I claim:

The ornamental design for a high pressure gauge housing, substantially as shown and described.
